CUTTER-CHAIN MACHINE FOR USE IN MINING COAL AND OTHER MINERALS

John Bridie Mavor, Glasgow, Scotland, assignor to Mavor and Coulson, Limited, Glasgow, Scotland

Application March 1, 1939, Serial No. 259,159
In Great Britain March 4, 1938

16 Claims. (Cl. 262—30)

This invention refers to cutter-chain machines for use in mining coal and other minerals.

In the specification of British Patent No. 329,837, granted to Mavor and Coulson, Limited and another, there is described a device for dealing with cuttings which emerge with the cutter-chain of a cutter-chain mining machine, the device in one construction comprising a helical conveyor operating transversely at the trailing side of the cutter-chain. Cuttings brought out by the chain are thrown off by the chain as it passes round the sprocket wheel and the device removes the cuttings from the vicinity of the cutter-chain and so to a large extent prevents the cuttings from being carried by the ingoing strand of the chain back into the cut, besides reducing the amount of dust raised and controlling the deposition of the cuttings.

In mining machines with which this invention is concerned, either of the two edges of the cutter-jib may be the leading or cutting edge. The change from one edge to the other as the cutting edge necessitates reversal of the direction of circulation of the cutter-chain on the jib and reversal of the drive from the chain-driving motor.

In some cases a helical cuttings conveyor arranged to operate in a longitudinal direction, instead of in a transverse direction, may be advantageous, and according to this invention, a conveyor arrangement is provided comprising a conveyor of helical type operating with its axis in a longitudinal direction relative to the machine and mechanism transmitting power from the motor means of the machine and applying it to drive the conveyor, the conveyor arrangement being designed to effect conveyance of cuttings rearwardly from the vicinity of the cutter-chain for both directions of circulation of the cutter-chain and both directions of operation of the motor means.

The direction of advance of the machine when cutting is, it will be understood, considered as being the longitudinal direction, but the term "longitudinal direction" as applied to the direction of operation of the helical conveyor is used in a general sense and does not imply that the conveyor necessarily operates strictly in the direction of advance of the machine. The line of operation may appreciably deviate therefrom, say as much as 40°, while still sweeping the cuttings in a direction which is in general longitudinal.

The invention will now be described with reference to the accompanying drawings, in which:

Figure 1 is a perspective view showing a coal

cutting machine with the helical conveyor attached.

Figure 2 is a plan view showing one form of the helical conveyor attached to the coal cutting machine.

Figure 3 is a view showing the conveyor attaching and driving mechanism of this form, the view being a transverse vertical section.

Figure 4 is a side elevation of this form of the machine.

Figure 5 is a plan view showing a second form of the invention.

Figure 6 is a transverse vertical section showing a third form of the invention.

Figure 7 is a view partly in section and partly in elevation and showing this third form of the invention.

Figure 1 illustrates the general arrangement of a coal cutting machine having this invention attached thereto. In this figure A' denotes the body of a coal cutting machine and E' the arm carrying the cutter chain. The helical conveyor and its drive are positioned on the machine at C'.

Figures 2, 3 and 4 show a construction in which a helical conveyor is arranged end-on to the cutter-chain of the machine A. The apparatus comprises a helical conveyor B, a carrier C, and an auxiliary gear box D at the rear of the machine A.

30 The auxiliary gear box is open at its two lateral ends and presents to each side a coupling or clutch part to act as a driving connection for the helical conveyor B, the couplings of the auxiliary gear box deriving their motion from the crown wheel on the cutter-chain driving sprocket wheel shaft within the gear head of the machine, as hereinafter more fully explained.

The conveyor B comprises a substantially cylindrical housing 2, a helix 3 on a shaft 4 within the housing 2, a gear case 5, and a tubular extension 6 from the gear case 5. Housing 2 is open at its forward end and has discharge openings 7 in its peripheral wall. The shaft 4 extends into the gear case 5 through a conical shield 8 and the gear case 5 contains a train of pinion wheels for the drive of the shaft 4. Under the shaft 4 between the openings 7 there is a plough or deflector 9.

40 The carrier C is constructed in the form of a clamp to grip the auxiliary gear box D, for which purpose it comprises a tubular part 10 and a transmission casing 12 joined by a connecting piece 13. Within the transmission casing 12 there is a shaft 14 which engages at its inner end with the adjacent coupling in the auxiliary

55

gear box D. This shaft 14 carries a bevel wheel 15 which meshes with a bevel wheel 16 on a longitudinal shaft 17 extending rearwards beyond the casing 12 and carrying at its rear end a pinion wheel 18. The conveyor unit B is secured to the carrier C by connection of the tubular extension 6 to the transmission casing 12, the pinion wheel 18 meshing with the uppermost pinion wheel of the gear train in the gear case 5. The carrier C and conveyor unit B are attached to the machine A by screw clamping action effected manually by operation of a head 19, rotation of which rotates a screw spindle 30 and thereby moves a tubular clamping piece 31 transversely so that the auxiliary gear box D is gripped between the clamping piece 31 and a complementary tubular part 33. Within the gear box D there is a transverse shaft 34 carrying a bevel wheel 35 near its centre and having at each of its ends a positive-engagement clutch coupling 36. The bevel wheel 35 meshes with a bevel wheel 37 on the rear end of a longitudinal shaft 38 which extends from within the body A of the mining machine into the auxiliary gear box and which is driven from the motor which drives the cutter-chain. When the carrier is clamped to the gear box D as shown in Figure 3, a clutch coupling 39 at the inner end of the carrier shaft 14 engages with the clutch coupling 36 at the adjacent end of the gear box shaft 34. Drive is transmitted from the motor by way of shaft 14, bevel wheels 15 and 16, shaft 17, pinion wheel 18, and train of pinion gearing in gear case 5 to the conveyor shaft 4. The helix 3 draws in cuttings at its forward end and ejects them through the openings as indicated in Figure 2, the plough 9 shedding the cuttings and facilitating their discharge. The conical shield 8 prevents cuttings passing into the gear case 5.

If the jib E of the machine A is to cut at the other side of the machine, the conveyor unit B and tubular extension 6 are freed from the carrier C, the carrier C is detached from the auxiliary gear box D, reversed end for end, and re-attached to the gear box D, and the conveyor unit B is made fast to the carrier C to occupy a position as indicated by the line 20, Figure 2, the clutch coupling 39 of the shaft 14 engaging with the clutch coupling 36 at the left hand end of the gear box shaft 34, Figure 3. In this way, for both positions of the carrier C, the helix 3 rotates in the same sense, the motor being reversed as between the two positions.

A guard plate 21 is fitted between the forward end of the conveyor unit B and the body of the machine and serves also as a stay for the conveyor structure, and a guide plate 22 is fitted as shown in Figure 2 to cause the cuttings to be kept in rapid motion as the chain passes round its sprocket wheel until they are released and directed into the housing 2.

In the example shown in Figure 5, a helical conveyor is shown arranged tangentially to the cutter-chain as the chain passes round the cutter-chain sprocket wheel. The conveyor B¹ comprises a substantially cylindrical housing 32 in the peripheral wall of which there is a receiving opening 23 and a discharge opening 24. The conveyor B¹ is mounted on the machine A by means of a carrier C¹ of somewhat similar construction to the carrier C shown in Figures 1 and 2, drive being transmitted from the auxiliary gear box D through a transmission casing 25 forming part of the carrier C¹, and then through a gear case 26 to the shaft of the helical conveyor. The 75

gear case 26 is removably attached to the carrier C¹ for purposes of fitting the conveyor at the other side of the machine when the carrier C¹ has been reversed.

The invention is equally applicable to overcutting machines, i. e. machines in which the cutter-chain cuts at a level substantially above that of the under side of the machine body.

In some overcutting machines, the cutter-jib is not mounted above the body, and the arrangement is then simply equivalent to that shown in Figures 1, 2 and 3 but with the machine turned upside down.

Where the cutter-jib is mounted above the level of the machine body by means of a turret or equivalent, extending upwards from the gear head, the helical conveyor occupies the same position relative to the gear head as in the case where the cutter-jib is not above the body, and a chute is provided to bring cuttings down to the conveyor.

In the form shown in Figures 6 and 7, A' denotes the coal cutting machine, B' the helical conveyor, and C' the carrier for the latter.

Referring firstly to Figure 7, this shows the crown wheel 1' driven by means not shown from the sprocket wheel which drives the cutter-chain 3'. An auxiliary gear box D' is fitted to the rear of the machine A', this gear box containing a longitudinal shaft 4' and two co-axial shafts 5' at right angles to the shaft 4'. At its forward end the shaft 4' has a bevel wheel 6' which engages with the crown wheel 1' and motion of the shaft 4' is transmitted to the shafts 5' by bevel wheels 7' and 1a'. At the outer end of each of the shafts 5' there is a coupling 8' of dog clutch type, the two couplings being directed towards opposite sides.

The conveyor B' comprises a casing 9' of substantially cylindrical form, and a helical conveyor 10' operating within the casing 9'.

The carrier C' comprises two tubular parts 11' directed towards one another with a gap between them to constitute a jaw or clamping arrangement for connection to the machine, A'. From the tubular parts 11', two arms 12' and 13' extend down to the conveyor casing 9'. Within the right hand tubular part 11' and the right hand arm 12', see Figure 6, transmission gearing is fitted. This gearing comprises a shaft 14' within the tubular part 11' and a train of pinion wheels 15' within the arm 12'. At the inner end (the central end) of the shaft 14' there is a coupling 16' of dog clutch type. The left hand tubular part 11' is telescopic, the inner portion thereof 11a' being slidable relatively to the outer portion, and for moving the portion 11a' there is a screw 17' with an operating head 18'. The inner end of the portion 11a' is formed as a socket, as is also the inner end of the right hand tubular part 11'.

To attach the helical conveyor means to the auxiliary gear box D' already mounted on the machine, the portion 11a' is screwed back to allow of the gear box D' being introduced into the gap between two tubular parts 11' of the carrier. The coupling part 16' of the carrier is engaged with the coupling part 8' of the right hand shaft 5' and the head 18' is screwed up so as to clamp the carrier to the gear box D'. The jib E' of the machine in Figures 1, 6 and 7 is assumed to be in position for cutting at the right hand side looking forward and the helix 10' extends more or less parallel with the trailing or ingoing strand of the cutter chain 3'. In the casing 9' there

are two similar openings, one at the leading side and the other at the trailing side. The opening at the trailing side is closed by a cover 19', see Figure 7, while the opening at the leading side of the casing is open to receive cuttings, which are swept to the left by the conveyor 10' and ejected from the casing 9'.

If the jib is to cut at the other side of the machine, the carrier C' is detached, reversed end for end, and reattached so that the drive to the conveyor is from the left hand shaft 5', the other shaft 5' running idle. The helix 10' is a push fit on its shaft 24', see Figure 6, and it is removed and a conveyor of opposite hand substituted.

I claim:

1. A mining machine having an elongated machine body, a cutter-chain, a jib carrying the cutter-chain and capable of operating at either side of the machine substantially at right angles to the length of the machine body, motor means within the machine body for driving the cutter-chain and including reversing means whereby the direction of circulation of the cutter-chain can be reversed in accordance with which of the two edges of the jib is the cutting edge, and conveyor means for dealing with cuttings which emerge with the cutter-chain, the conveyor means being constructed as a unit attachable to and detachable from the machine and comprising a conveyor of helical type, power transmission mechanism, means for securing the unit to the machine in either of two alternative positions so that the conveyor is in a position to operate in a longitudinal direction relative to the machine at a position offset laterally from the center line of the machine body at whichever side is remote from that at which the cutter-chain is operating, to remove cuttings rearwardly from the vicinity of the cutter-chain, and a coupling device forming part of the transmission mechanism of the conveyor unit, with transmission mechanism on the machine body for the transmission of power from the motor means aforesaid and a coupling device forming part of the transmission mechanism of said machine body and engageable by the coupling device of the conveyor unit when the latter is attached to the machine in either of the two positions, the change of position providing for the rotation of the conveyor being maintained in the same sense despite reversal of the motor means of the machine necessitated by changing the position of the cutter-chain from one side to the other.

2. A mining machine having a machine body, a cutter-chain, a jib carrying the cutter-chain and projecting from the machine body, motor means within the machine body for driving the cutter-chain and including reversing means whereby the direction of circulation of the cutter-chain on the jib can be reversed in accordance with which of the two edges of the jib is the cutting edge, a conveyor of helical type to carry away cuttings which emerge with the cutter-chain, a carrier for the attachment of the conveyor to the machine body so that the conveyor operates in a longitudinal direction relative to the machine body, transmission mechanism embodied in the carrier for the drive of the conveyor, mounting means on the machine body to receive the carrier, a driving connection included in the mounting means for detachably securing the carrier to the mounting means in either of two positions differing in that the carrier is reversed end for end, the carrier thus providing for support of the conveyor in either of two different

positions in accordance with the side of the machine at which the cutter-chain is cutting, the conveyor acting rearwardly in both such positions, and a coupling forming part of the transmission mechanism of the carrier to engage with the driving connection aforesaid in either of the two positions of attachment, to complete the drive to the conveyor.

3. A mining machine having a machine body, a cutter-chain, a jib carrying the cutter-chain and projecting from the machine body, motor means within the machine body for driving the cutter-chain and including reversing means whereby the direction of circulation of the cutter-chain on the jib can be reversed in accordance with which of the two edges of the jib is the cutting edge, a conveyor of helical type to carry away cuttings which emerge with the cutter-chain, a carrier for the attachment of the conveyor to the machine body, transmission mechanism embodied in the carrier for the drive of the conveyor, mounting means on the machine body to receive the carrier, a driving connection included in the mounting means, clamping jaws on the carrier for detachably securing the carrier to the mounting means in either of two positions differing in that the carrier is reversed end for end, the carrier thus providing for support of the conveyor in either of two different positions in accordance with the side of the machine at which the cutter-chain is cutting so that in both positions the conveyor operates rearwardly in a longitudinal direction relative to the machine body, and a coupling forming part of the transmission mechanism of the carrier to engage with the driving connection aforesaid in either of the two positions of attachment, to complete the drive to the conveyor.

4. Conveyor means for dealing with cuttings which emerge with the cutter-chain of a cutter-chain mining machine, comprising a conveyor to carry away the cuttings, a carrier for the attachment of the conveyor to the mining machine, transmission mechanism embodied in the carrier for the drive of the conveyor, mounting means on the machine to receive the carrier, a driving connection included in the mounting means, means for detachably securing the carrier to the mounting means in either of two positions differing in that the carrier is reversed end for end, the carrier thus providing for support of the conveyor in either of two different positions in accordance with the side of the machine at which the cutter-chain is cutting, and a coupling forming part of the transmission mechanism to engage with the driving connection aforesaid in either of the two positions of attachment, to complete the drive to the conveyor.

5. Conveyor means for dealing with cuttings which emerge with the cutter-chain of a cutter-chain mining machine, comprising a conveyor to carry away the cuttings, a carrier for the attachment of the conveyor to the mining machine, transmission mechanism embodied in the carrier for the drive of the conveyor, mounting means on the machine to receive the carrier, a driving connection included in the mounting means, securing means for detachably securing the carrier to the mounting means in either of two positions differing in that the carrier is reversed end for end, the carrier thus providing for support of the conveyor in either of two different positions in accordance with the side of the machine at which the cutter-chain is cutting, a single actuating member by manipulation of which the se-

curing means are operated, and a coupling forming part of the transmission mechanism to engage with the driving connection aforesaid in either of the two positions of attachment, to complete the drive to the conveyor.

6. Conveyor means for dealing with cuttings which emerge with the cutter-chain of a cutter-chain mining machine, comprising a conveyor to carry away the cuttings, a carrier for the attachment of the conveyor to the mining machine, transmission mechanism embodied in the carrier for the drive of the conveyor, mounting means on the machine to receive the carrier, a driving connection included in the mounting means, clamping jaws for detachably securing the carrier to the mounting means in either of two positions differing in that the carrier is reversed end for end, the carrier thus providing for support of the conveyor in either of two different positions in accordance with the side of the machine at which the cutter-chain is cutting, and a coupling forming part of the transmission mechanism to engage with the driving connection aforesaid in either of the two positions of attachment, to complete the drive of the conveyor.

7. Conveyor means for dealing with cuttings which emerge with the cutter-chain of a cutter-chain mining machine, comprising a conveyor to carry away the cuttings, a carrier for the attachment of the conveyor to the mining machine, transmission mechanism embodied in the carrier for the drive of the conveyor, mounting means on the machine to receive the carrier, a driving connection included in the mounting means, clamping jaws for detachably securing the carrier to the mounting means in either of two positions differing in that the carrier is reversed end for end, the carrier thus providing for support of the conveyor in either of two different positions in accordance with the side of the machine at which the cutter-chain is cutting, a single actuating member by manipulation of which the clamping jaws are operated, and a coupling forming part of the transmission mechanism to engage with the driving connection aforesaid in either of the two positions of attachment, to complete the drive to the conveyor.

8. Conveyor means for dealing with cuttings which emerge with the cutter-chain of a cutter-chain mining machine, comprising a conveyor to carry away the cuttings, a carrier for the attachment of the conveyor to the mining machine, transmission mechanism embodied in the carrier for the drive of the conveyor, mounting means on the machine to receive the carrier, a driving connection included in the mounting means, and clamping jaws on the carrier for detachably securing the carrier to the mounting means in either of two positions differing in that the carrier is reversed end for end, the carrier thus providing for support of the conveyor in either of two different positions in accordance with the side of the machine at which the cutter-chain is cutting, the transmission mechanism extending from one of the clamping jaws by way of the carrier to the conveyor and comprising a coupling to engage with the driving connection aforesaid in either of the two positions of attachment, to complete the drive to the conveyor.

9. Conveyor means for dealing with cuttings which emerge with the cutter-chain of a cutter-chain mining machine, comprising a conveyor to carry away the cuttings, a carrier for the attachment of the conveyor to the mining ma-

chine, transmission mechanism embodied in the carrier for the drive of the conveyor, mounting means on the machine to receive the carrier, a driving connection included in the mounting means, clamping jaws on the carrier for detachably securing the carrier to the mounting means in either of two positions differing in that the carrier is reversed end for end, the carrier thus providing for support of the conveyor in either of two different positions in accordance with the side of the machine at which the cutter-chain is cutting, and a single actuating member by manipulation of which the clamping jaws are operated, the transmission mechanism extending from one of the clamping jaws by way of the carrier to the conveyor and comprising a coupling to engage with the driving connection aforesaid in either of the two positions of attachment, to complete the drive to the conveyor.

10. Conveyor means for dealing with cuttings which emerge with the cutter-chain of a cutter-chain mining machine, comprising a conveyor of helical type to carry away the cuttings, a carrier for the attachment of the conveyor to the mining machine, transmission mechanism embodied in the carrier for the drive of the conveyor, mounting means on the machine to receive the carrier, a driving connection included in the mounting means, means for detachably securing the carrier to the mounting means in either of two positions differing in that the carrier is reversed end for end, the carrier thus providing for support of the conveyor in either of two different positions in accordance with the side of the machine at which the cutter-chain is cutting, and a coupling forming part of the transmission mechanism to engage with the driving connection aforesaid in either of the two positions of attachment, to complete the drive to the conveyor.

11. Conveyor means for dealing with cuttings which emerge with the cutter-chain of a cutter-chain mining machine, comprising a conveyor of helical type to carry away the cuttings, a carrier for the attachment of the conveyor to the mining machine, transmission mechanism embodied in the carrier for the drive of the conveyor, mounting means on the machine to receive the carrier, a driving connection included in the mounting means, clamping jaws for detachably securing the carrier to the mounting means in either of two positions differing in that the carrier is reversed end for end, the carrier thus providing for support of the conveyor in either of two different positions in accordance with the side of the machine at which the cutter-chain is cutting, and a coupling forming part of the transmission mechanism to engage with the driving connection aforesaid in either of the two positions of attachment, to complete the drive to the conveyor.

12. Conveyor means for dealing with cuttings which emerge with the cutter-chain of a cutter-chain mining machine, comprising a conveyor of helical type to carry away cuttings, a carrier for the attachment of the conveyor to the mining machine, transmission mechanism embodied in the carrier for the drive of the conveyor, mounting means on the machine to receive the carrier, a driving connection included in the mounting means, and clamping jaws on the carrier opening and closing in a direction parallel with that in which the axis of the conveyor extends for detachably securing the carrier to

the mounting means in either of two positions differing in that the carrier is reversed end for end with consequent reversal of the conveyor end for end in accordance with the side of the machine at which the cutter-chain is cutting, the transmission mechanism extending from one of the clamping jaws by way of the carrier to the conveyor at one end thereof and comprising a coupling to engage with the driving connection aforesaid in either of the two positions of attachment, to complete the drive to the conveyor.

13. A mining machine of the cutter-chain type having conveyor means for dealing with cuttings which emerge with the cutter-chain, comprising a conveyor to carry away the cuttings, a carrier for the attachment of the conveyor to the mining machine, transmission mechanism embodied in the carrier for the drive of the conveyor, mounting means on the machine to receive the carrier, a driving connection included in the mounting means, means for detachably securing the carrier to the mounting means in either of two positions differing in that the carrier is reversed end for end, the carrier thus providing for support of the conveyor in either of two different positions in accordance with the side of the machine at which the cutter-chain is cutting, and a coupling forming part of the transmission mechanism to engage with the driving connection aforesaid in either of the two positions of attachment, to complete the drive to the conveyor.

14. A mining machine of the cutter-chain type having conveyor means for dealing with cuttings which emerge with the cutter-chain which is driven by a sprocket wheel, comprising a conveyor of helical type to carry away cuttings, a carrier for the attachment of the conveyor to the mining machine, transmission mechanism embodied in the carrier for the drive of the conveyor, mounting means on the machine to receive the carrier, a driving connection included in the mounting means, clamping jaws on the carrier opening and closing in a direction approximately at right angles to that in which the axis of the conveyor extends, for detachably securing the carrier to the mounting means in either of two positions differing in that the carrier is reversed end for end, the carrier thus providing for support of the conveyor in either of two different positions in accordance with the side of the machine at which the cutter-chain is cutting, the transmission mechanism extending from one side of the clamping jaw by way of the carrier to the conveyor at one end thereof and comprising a coupling to engage with the driving connection in either of the two positions of attachment, to complete the drive to the conveyor, and a guide

of arcuate form following the path of the chain as it passes round the driving sprocket wheel, to guide cuttings into the conveyor.

15. A mining machine of the cutter-chain type having conveyor means for dealing with cuttings which emerge from the cutter-chain which is driven by a sprocket wheel, comprising a conveyor of helical type to carry away cuttings, a carrier for the attachment of the conveyor to the mining machine, transmission mechanism embodied in the carrier for the drive of the conveyor, mounting means on the machine to receive the carrier, a driving connection included in the mounting means, clamping jaws on the carrier opening and closing in a direction approximately at right angles to that in which the axis of the conveyor extends, for detachably securing the carrier to the mounting means in either of two positions differing in that the carrier is reversed end for end, the carrier thus providing for support of the conveyor in either of two different positions in accordance with the side of the machine at which the cutter-chain is cutting, the transmission mechanism extending from one side of the clamping jaws by way of the carrier to the conveyor at one end thereof and comprising a coupling to engage with the driving connection in either of the two positions of attachment, to complete the drive to the conveyor, and a guard plate fitted at the side of the machine away from that at which the chain is cutting between the conveyor and the machine at a position in front of the chain.

16. A mining machine of the cutter-chain type having conveyor means for dealing with cuttings which emerge with the cutter-chain, comprising a conveyor to carry away the cuttings, a carrier for the attachment of the conveyor to the mining machine, transmission mechanism embodied in the carrier for the drive of the conveyor, mounting means on the machine to receive the carrier, a driving connection included in the mounting means, means for detachably securing the carrier to the mounting means in either of two positions differing in that the carrier is reversed end for end, the carrier thus providing for support of the conveyor in either of two different positions in accordance with the side of the machine at which the cutter-chain is cutting, a coupling forming part of the transmission mechanism to engage with the driving connection aforesaid in either of the two positions of attachment, to complete the drive to the conveyor, and a guard plate fitted at the side of the machine away from that at which the chain is cutting between the conveyor and the machine at a position in front of the chain.

JOHN BRIDIE MAVOR.
